MOTOR-CONTROLLED AUTOMOBILE RADIO ANTENNA

Joseph B. Cejka, Highland Park, N.J., assignor to General Bronze Corporation, Garden City, N.Y., a corporation of New York

Filed June 13, 1956, Ser. No. 591,115

1 Claim. (Cl. 343—714)

This invention relates to collapsible whip-type radio antennas for automobiles and other vehicles, and particularly to antennas of the type comprising a plurality of telescoping sections of metal tubing which are extended and retracted by means of a length of flexible cable secured to the innermost section of the antenna.

It is among the objects of the present invention to provide a mechanical arrangement for driving the flexible cable which is practical and reliable in its operation, although relatively simple and inexpensive in construction. It is a further object to provide such an antenna wherein there is a positive driving engagement with the cable whereby slippage at this point is eliminated and wherein the cable is engaged along a considerable portion of its length to distribute the strain imposed on the cable and thereby reduce the possibility of cable failure. Another object is that of providing in such an antenna facilities for storing and guiding the cable of such construction that the cable may be driven in either direction without appreciable hazard of binding, kinking or jamming. Other and further objects will be in part specifically pointed out and in part apparent from the ensuing description.

In the drawings:

Figure 1 is a side elevational view of an antenna embodying features of the present invention with the antenna, with the length of the antenna reduced by showing it broken at several points and with it shown partly in vertical section.

Figure 2 is a greatly enlarged fragmentary side elevational view of the housing at the lower end of the antenna of Figure 1, with the housing being shown partly in vertical section.

Figure 3 is a fragmentary vertical sectional view of a portion of the mechanism shown in Figure 2.

Figure 4 is a somewhat diagrammatic elevational view of the gear train of the mechanism shown in Figure 2.

Figure 5 is an exploded view of the cable driving, guiding and storing components of the mechanism shown in Figure 2, shown at a scale slightly reduced relative to that of Figure 2.

Figure 6 is a schematic diagram of the electrical control circuit of the antenna.

Figure 7 is a side elevational view of the upper portion of the antenna, at the approximate scale of Figure 2, with the antenna shown partially broken away to reveal its inner construction.

Figure 8 is an isometric view of the switch-operating cam of the mechanism shown in Figure 2.

Figure 9 is an end elevational view of the cam shown in Figure 8.

As may be seen in Figure 1, the antenna generally comprises a whip portion 10, a mounting base 12, a tubular extension 14, an electric motor 16 and a housing 18 which contains the driving mechanism associated with the motor 16 and the facilities for guiding and storing the flexible cable, as well as the cam-operated limit switches which control the motor.

2

As may be seen in Figure 7, the whip portion of the antenna comprises four sections, a fixed outer tubular section 20, intermediate tubular telescoping sections 22 and 24, and an innermost section 26 of flexible solid rod. Each of the inner sections 22, 24 and 26 is longitudinally slidable relative to the adjacent outer section. The two intermediate sections 22 and 24 are provided at their lower ends with external collars 28 which engage internal circumferential beaded ribs which are swaged in the adjacent outer sections near their lower ends to limit the downward movement of the sections 22 and 24. Their upward movement is limited by engagement of the collars 28 with similar beadings 32 near the upper ends of the adjacent outer sections. Downward movement of the innermost section 26 is limited by engagement of a finial or tip 34 fixed at its upper end with the upper end of the adjacent section 24. Upward movement of the innermost section 26 is limited by engagement between the beading 32 near the upper end of the adjacent section 24 and the ferrule 36 by which the lower end of the innermost section 34 is spliced to the upper end of the flexible cable 38.

The flexible cable 38 is formed of two helically wound steel springs, the smaller of which forms the core of the cable and the larger of which is wrapped tightly around the smaller with the turns of the larger held in spaced relation to each other by engagement with the turns of the inner spring so that they are capable of functioning as rack teeth.

30 The outermost section 20 of the antenna is fixedly supported in insulated relation to the base 12 by a plastic sleeve 40. The base 12 extends through an opening 42a in the automobile body 42 and is secured in fixed position relative thereto by a pair of toggle members 44 which are pivotally mounted at either side of the base 12 and which engage the undersurface of the automobile body 42. A nut 46 (Figure 1) is threaded on the upper portion 12a of the base 12 and bears downwardly against a generally hemispherical insulator 48 which in turn bears against a rubber washer 50 which is interposed between it and the outer surface of the automobile body 42. The pivotal mounting of the toggle members 44 and the wedge shape of the slot 42a in the hemispherical insulator 48 through which the base 12 passes (see Figure 1) permits the antenna to be mounted in a vertical position although the adjacent portion of the automobile body 42 may be inclined at a considerable angle with respect to the horizontal.

Extending downwardly from the base 12 is an extension tube 14 which receives the sections of the antenna whip when they are in their retracted position, in which they are shown in Figure 7. The upper end of the tubular extension 14 is received in the lower end of the base 12 and is secured thereto by screws 54 (Figures 1 and 7).

55 Electrical connection is made to the antenna through a threaded nipple connector 56 integrally formed on a skirt 12b which depends downwardly from the lower edge of the base 12. This nipple connector 56 contains a male connector prong 58 which is supported at the central axis of the connector and in insulated relation thereto by an annular spacer 60. The prong 58 and the nipple 56 thus form a male coaxial connector adapted for connection to a conventional female connector of a coaxial transmission line which is used to conduct the signal picked up by the antenna to the radio receiver. The male prong 58 of the connector assembly is electrically connected to the fixed outer section 20 of the antenna through a capacitor 62, the pigtail leads of which are respectively soldered to the outer section 20 and to the male prong 58. The nipple 56 and the integral body 64 are grounded to the automobile body through the toggle members 44.

members 44 which have sharp projecting prongs at their corners for piercing any undercoating on the automobile body and making good electrical contact with the body. This grounded connection may be augmented, if desired, by means of a terminal post 18a (Figure 1) integrally formed at the lower side of the metal housing 18.

The lower end of the fixed outer section 20 of the whip is supported in the extension tube 14 by means of an insulating spacer 64 which includes a central passageway lined with a tube 66 of insulating material through which the flexible cable 38 passes. Secured to the lower end of the extension tube 14 by means of screws 68 is the neck 18a of the housing 18 (see Figure 1).

Generally speaking, the housing 18 includes a tubular shell 70 (Figure 2) which is closed at one end by an end plate 72 and at its other end by a cast plate 74 which has integrally formed thereon a shallow cup-like portion 74a which receives and supports one end of the electric motor 16. Extending across the shell 70 is an integral supporting wall 70a which includes, at the central axis of the shell, a bearing sleeve 76 which rotatably supports a drive shaft 78.

Secured at one end of this drive shaft 78 is a clutch assembly which is generally indicated 80 in Figure 2, and which is shown in greater detail in Figure 3. As may be seen in the latter figure, this clutch assembly includes a clutch plate 82, the hub portion 82a of which is keyed to the drive shaft 78 by means of a pin 84 which is received in registering longitudinal slots formed in the outer surface of the shaft 78 and in the inner surface of the hub 82a. The clutch plate 82 is held on the end of the drive shaft 78 by means of a retaining ring 86 which is received in a peripheral slot 78a in the end of the drive shaft, with a washer 88 interposed between the retaining ring 86 and the outer end of the hub 82a. The face of the clutch plate 82 is provided with a series of spaced shallow indentations 82b in which are partially received an equivalent number of ball bearings 90 which are interposed between the face of the clutch plate and the adjacent face of a spur gear 92 which is similarly provided with shallow indentations to partially receive the ball bearings 90. The gear 92 is resiliently urged toward the clutch plate 82 by means of a spring cup washer 94 (see also Figure 2) which is interposed between the adjacent face of the gear 92 and a retaining ring 96 which is received in a peripheral slot 78b in the drive shaft 78.

When the gear 92 is driven, the drive shaft 78 is normally driven with it through the clutch 80. However, when the resistance imposed upon the drive shaft 78 reaches a predetermined level, the ball bearings 90 are cammed out of the indentations in the clutch plate 82 and/or the gear 92, forcing these two members slightly apart against the resistance of the spring cup washer 94 and allowing relative rotation between them to cause the ball bearings 90 to move from their respective indentations on one or both of these members into the adjacent indentations, thus allowing incremental "slippage" or "indexing" of the clutch 80 so long as the resistance continues, or until the driving power supplied to the gear 92 is cut off. This arrangement thus limits the amount of driving power which can be supplied to the drive shaft 78.

The gear 92 is driven from the electric motor 16 through a pinion 98 which is fixed on the shaft 100 of the motor 16. This pinion 98 engages a spur gear 102 fixed on a shaft 104 which is journaled in the wall 70a and in the end plate 72 and on which is also fixed pinion 106. This pinion 106 meshes with a spur gear 108 fixed on a shaft 110 which is journaled in the wall 70a and in the end plate 72 and on which is also fixed a pinion 112 which meshes with the gear 92. Thus, whenever the motor 16 is running, it drives the gear 92 at a reduced speed, and this gear in turn drives the drive shaft 78 through the clutch 80 except where the resistance imposed on the drive shaft 78 exceeds the level sufficient to cause indexing of the clutch 80, as previously described.

Fixed on the end of the drive shaft 78 which projects through the supporting wall 70a into the left-hand end of the housing 18, as viewed in Figure 2, is a cable-driving gear 114, the hub portion 116 of which is formed of insulating material such as nylon, and the peripheral portion 117 of which is formed of a hard material such as steel. The outer edge of the peripheral portion 117 is circumferentially grooved to receive the cable 38 and is shaped to receive the "teeth" on the cable. The two portions 116 and 117 of the gear 114 are secured together by screws 119. The gear 114 is rotatably received within a central chamber 118 defined by a recess 120a in a guide member 120 and by the cup-shaped cover plate 122. Both the guide member 120 and the cover plate 122 are formed of a plastic insulating material such as nylon, and they interfit with one another to form a generally wafer-shaped assembly of an outside diameter slightly smaller than the inside diameter of the shell 70. This assembly is secured together and supported within the shell 70 by means of screws 124 which extend through holes in the guide member 120 and cover plate 122 and are threaded into the adjacent face of the supporting wall 70a.

As may be seen in Figure 5, the central chamber 118 of the guide assembly is generally circular in cross section. It is just deep enough to admit the flexible cable 38 and is of a diameter just sufficient to permit the flexible cable to be wrapped around the periphery of the gear 114 without excessive friction between the flexible cable 38 and the walls of the chamber 118. The guide assembly 120, 122 thus serves to maintain the flexible cable 38 in driving engagement with the gear 114. The guide member 120 is provided with a vertical slot 120b which merges tangentially with the circular chamber 118 and through which the cable 38 passes into the chamber. The cover plate 122 is provided with a notch 122a to provide clearance for the cable.

As best shown in Figure 5, the central chamber 118 is provided at one side with a spiral slot 126 which merges tangentially with the chamber 118 and which extends from the chamber 118 on a path of gradually increasing radius of curvature. The depth of the slot 126 increases as the slot progresses from the central chamber 118, so that the slot ultimately extends through the opposite face of the guide member 120. The cover plate 122 is provided with a spiral ramp 128 (Figure 5) which is adapted to be received in the passageway 126 when the guide member 120 and cover plate 122 are assembled. The outer surface of the ramp 128 is spaced from the inner wall of the passageway 126 by a uniform distance sufficient to pass the flexible cable 38 so that the ramp 128 and the passageway 126 together define a passageway for the flexible cable 38 which, as previously mentioned, is on a gradually increasing radius of curvature, as well as being gradually deflected from the plane of the gear 114 toward the left, as viewed in Figures 2 and 5, until the flexible cable 38 passes completely through the guide member 120.

Mounted at the left-hand side of the guide member 120, as viewed in Figures 2 and 5, is a reel 130, the hub portion 130a of which is rotatably supported on the drive shaft 78, with the reel 130 being held on the end of the drive shaft 78 by a retaining ring 132 (Figure 2).

The reel 130 is provided with an outer generally cylindrical flange 130b and an inner cylindrical flange 130c, both of which are coaxial with the reel and which are spaced apart to define an annular storage chamber 130d.

The edges of the flanges 130b and 130c fit flush against the adjacent surfaces of the guide member 120 with the storage chamber 130d opposite the opening in the guide member 120 through which the flexible cable passes. Thus, the spiral course of the flexible cable 38 carries it into the storage chamber 130d.

When the gear 114 is rotated by the motor 16 in a clockwise direction, as viewed in Figure 5, it pulls the

flexible cable 38 downwardly from the upper portions of the antenna assembly and pushes them through the guide assembly 120, 122 into the storage chamber 130d of the reel 130. Because the flexible cable 38 resists bending, it tends to engage the inner surface of the outer flange 130b of the reel 130, as shown in Figure 2. The inner surface of this outer flange 130b is slightly tapered —i.e., its diameter at the input or right-hand end of the reel 130, as viewed in Figure 2, is slightly larger than its diameter at the left-hand end of the reel. Thus, the turns of the cable tend to remain near the input or right-hand end of the reel until they are pushed farther into the reel as additional turns are added to the store of cable 38 in the storage chamber 130d.

Since the reel 130 is rotatable relative to the shaft 78, the reel rotates as the cable 38 is pushed into it or pulled from it so that there is little, if any, longitudinal movement of the cable 38 relative to the surface or surfaces of the reel with which it is in engagement. This arrangement allows the cable 38 to be fed into or removed from the reel 38 without appreciable friction and without any substantial danger of binding, kinking or jamming.

When the motor 16 is driven to rotate the gear 114 in a counterclockwise direction, as viewed in Figure 5, the cable 38 is removed from the reel 130 and is forced upwardly within the antenna structure, first to drive the innermost section 26 of the antenna upwardly to a fully extended position at which the ferrule 36 engages the beading 32 near the upper end of the next adjacent outer section 24. Beyond this point, the inner section 26 carries the adjacent section 24 upwardly until it reaches a fully extended position at which it carries the next outer section 22 up to its fully extended position. When this point is reached, the cable 38 cannot move up any farther and the clutch 80 will index until the motor 16 is shut off. When the motor 16 is driven in the opposite direction the cable 38 will be pulled down to return the antenna to the fully retracted position in which it is shown in Figure 7, whereupon the clutch 80 will index until the motor 16 is shut off.

Electrical control means are provided by which the motor 16 may be automatically shut off after a number of revolutions at least sufficient to drive the antenna all the way up or all the way down. Means are also provided to cause the antenna, which is normally maintained in a fully retracted position when the automobile radio is turned off, to be driven automatically to a partially extended position each time the automobile radio is turned on. From this position, the electric motor 16 may be energized under manual control either to drive the antenna all the way up or to return it to the partially extended position. Then, when the automobile radio is turned off, the motor is automatically energized to drive the antenna to a fully retracted position.

This control means includes a switch-operating cam 134 (see particularly Figure 4) fixed on a shaft 136 which is rotatably journaled in the supporting wall 70a (Figure 2) and in the end plate 72. This cam 134 is provided at its periphery with spur gear teeth 137 (see particularly Figure 2) which are engaged by a pinion 138 (Figure 4) fixed on a rotatably mounted shaft 140 on which is also fixed a spur gear 142. The spur gear 142 meshes with a pinion 144 which is fixed on a rotatable shaft 146 on which is also fixed a spur gear 148. The latter spur gear 148 meshes with the main gear 92 which is driven by the electric motor 16 (Figure 2) as previously described. The ratio of gear reduction between the main gear 92 and the cam 134 is such that the cam 134 makes a little less than a full revolution each time the main gear 92 and the drive gear 114 (Figure 2) make a number of revolutions sufficient to drive the cable 38 from one extreme position of the antenna to the other plus a safety margin to insure full movement of the antenna.

As best shown in Figures 8 and 9, the cam 134 co-

operates with a switch generally indicated 150, having three sets of normally open, single-pole, single-throw contacts 152, 153 and 154. As best shown in Figure 9, the contacts 152 and 153 are arranged to cooperate with the outer marginal portion 149 of the face of the cam 134, while the contacts 154 are offset (see Figure 8) so that they cooperate with an elevated inner portion 151 of the cam 134.

In Figures 8 and 9 the cam 134 is shown in the position which it occupies when the antenna is fully retracted. In this position, the switch contacts 153 are in engagement with the surface 149 of the cam and are held closed, and the switch contacts 154 are in engagement with the elevated portion 151 of the cam 134 and are also closed. The switch contacts 152 are opposite a cut-out 155 in the cam and are therefore open. This is the condition of the switch contacts during periods when the automobile radio is not in use.

Figure 6 shows the method of connection of the switch 150 in the circuit which controls the electric motor 16. The motor 16 has two field windings, one of which is energized to rotate the motor in the direction to drive the cable 38 up, and the other of which is energized to drive the cable down. The motor is provided with three leads 156, 158, and 160 (Figure 6). The lead 156 is a common lead and is connected to one terminal 162a of a source of direct current, such as an automobile storage battery 162. The lead 158 of the motor connects with the field winding which is energized for driving the motor 16 in such direction as to drive the antenna downwardly. It is externally connected through the contacts 152 of the cam-operated switch 150 to one of the fixed contacts 164a of a single-pole, double-throw switch 164, which is mounted within the automobile radio and which is automatically actuated when the automobile radio is turned on and off, and is additionally connected to one of the fixed contacts 166a of a manually operated, normally open, momentary contact single-pole, double-throw switch 166, which is used for manual control of the antenna position.

The lead 160 of the motor 116 connects to the field winding which is energized for driving the antenna upwardly. This lead is externally connected through the contacts 153 of switch 150 to the other fixed contact 166b of the manual control switch 166. This "up" lead 160 is also connected through the other contacts 154 of the switch 150 with the other fixed contact 164b of the switch 164. The movable contacts 164c and 166c of the two switches 164 and 166 respectively are connected to the other terminal 162b of the power source 162.

It thus may be seen that the common lead 156 of the motor 16 is always connected to one terminal of the power source, so that the motor will rotate in one direction or the other when the other terminal of the source is connected to one of the leads 158 or 160.

Assume that the antenna is in its fully retracted position, with the switch contacts 153 and 154 closed as shown in Figure 8. When the automobile radio is turned on, the switch 164 (Figure 6) is thrown from the position shown in full lines to the position shown in broken lines at which its movable contact 164c is in engagement with its fixed contact 164b. This connects the terminal 162b of the power source through the switch 164 and through the closed contacts 154 of the switch 150 to the "up" lead 160 of the motor 16. This causes the motor 16 to run in the direction for driving the antenna upwardly.

When the antenna reaches a position approximately half-way between its retracted and fully extended positions, the cam 134 (Figures 8 and 9) will have rotated to such position that the contacts of switch 150 will ride off the edge 151a of the elevated portion 151 of the cam 134. This will open the contacts 154 and break the circuit to the motor 16, causing the antenna to stop in a partially extended position. This is the position in which

the antenna is normally maintained for driving in areas local to the station being received—that is, in areas of relatively high signal strength.

If it is desired to raise the antenna to a fully extended position, for example in remote areas, the manual switch 166 may be thrown to the "up" position, bringing its movable contact 166c into engagement with its fixed contact 166b. This connects the terminal 162b of the power source through the switch 166 and through the closed contacts 153 of the switch 150 to the lead 160 of the motor 16. This causes the motor to run in such direction as to drive the antenna upwardly. When the antenna reaches its fully extended position, the clutch 80 (Figures 2 and 3) will index until the motor 16 is shut off. The motor will continue to run until the contacts 153 of the switch 150 ride off the edge 149a of the marginal portion 149 of the cam 134, thereby opening the contacts 153 and breaking the circuit to the motor 16.

With the antenna fully extended, if it is desired to lower the antenna to its partially extended position, the manual switch may be thrown to the "down" position, bringing its movable contact 166c into engagement with its fixed contact 166a. This completes the circuit from the terminal 162b of the power source through the switch 166 and through the now closed contacts 152 of the switch 150 to the lead 158 of the motor 16. This causes the motor to rotate in such direction as to drive the antenna downwardly. When the antenna reaches its fully retracted position, the clutch 80 will index until the motor 16 is shut off. As the motor continues to run, the contacts 152 of switch 150 will ride off the edge 149a of the marginal portion 149 of the cam 134, opening the contacts 152, breaking the circuit to the motor 16 and shutting it off.

However, if the radio is still on, a circuit will be completed from the terminal 162b of the power source through the contacts 164c and 164b of the radio switch 164 and through the now closed contacts 154 of the switch 150 to the "up" lead 160 of the motor 16. This will cause the motor to run in such direction as to drive the antenna upwardly to its partially extended position, as previously described, at which point the contacts 154 will ride off the edge 151a of the cam 134, stopping the motor 16.

Whenever the radio is turned off, the switch 164 is actuated to bring its movable contact 164c into engagement with its fixed contact 164a, as shown in full lines in Figure 6, completing the circuit from the terminal 162b of the power source 162 through the switch contacts 164c and 164a and through the closed contacts 152 of the switch 150 to the "down" lead 158 of the motor 16. This will drive the motor in such direction as to lower the antenna until it reaches its fully retracted position and the motor is cut off by the contacts 152 riding off the edge 149b of the cam 134.

It will thus be apparent that the present invention provides a practical mechanism for controlling a motor-actuated whip-type antenna which is reliable in operation and relatively inexpensive in construction, and which is capable of both manually and automatically controlled movement to any of several predetermined positions.

It will therefore be appreciated that the aforementioned and other desirable objectives have been achieved. However, it should be emphasized that the particular embodiment of the invention which is shown and described herein is intended as merely illustrative rather than as restrictive of the invention.

I claim:

In an extensible automobile radio antenna of the type having a plurality of telescoping sections of different diameter, and a mounting base for supporting the outer section in insulated relation to the automobile body, means for raising and lowering said antenna comprising a flexible cable attached at its upper end to the innermost of said telescoping sections, said cable having regularly spaced surface serrations adapted to serve as rack teeth, a housing mounted at the lower end of said base, a drive gear in said housing, said drive gear having its periphery shaped to interfit with said serrations of said cable, an electric motor mounted on said housing, a slipping clutch connecting said motor to said drive gear, a first electrical switch arranged to be actuated when the automobile radio is turned on and off to connect said motor to a source of electrical current to cause it to drive said antenna upwardly when said radio is turned on and downwardly when it is turned off, second, third and fourth electrical switches mounted on said housing and connected to control the supply of current from said source to said motor, a composite switch operating member mechanically coupled to said drive gear to be driven with it by said motor, said switch operating member having switch operating surfaces cooperating with each of said second, third and fourth switches, whereby to actuate said second switch to stop said motor after said drive gear has made a number of rotations sufficient to drive said antenna up to a partially extended position, to actuate said third switch to stop said motor after said drive gear has made an additional number of rotations at least sufficient to drive said antenna up to a fully extended position, and to actuate said third switch to stop said motor after said drive gear has made a number of turns in the reverse direction at least sufficient to drive said antenna down to a retracted position, and a fifth, manually operated switch interconnected with said second, third and fourth switches whereby said motor can be connected to said source to be driven in either direction under manual control.
